US00D599770S

(12) **United States Design Patent**
Salmi et al.

(10) **Patent No.:** US D599,770 S
(45) **Date of Patent:** ** Sep. 8, 2009

(54) **HANDSET**

(75) Inventors: **Pertti Salmi**, Oulu (FI); **Hanna Vuolteenaho**, Oulu (FI)

(73) Assignee: **Nokia Corporation**, Espoo (FI)

(**) Term: **14 Years**

(21) Appl. No.: **29/327,173**

(22) Filed: **Oct. 31, 2008**

(51) **LOC (9) Cl.** 14-03

(52) **U.S. Cl.** ..... **D14/138 AD**

(58) **Field of Classification Search** ..... D14/138 R,
D14/138 AD, 138 AC, 138 C, 138 G, 191,
D14/203.1–203.8, 496, 138 AA, 138 AB,
D14/247–248, 137, 147, 218, 341–347; D10/65,
D10/78, 104; D13/168; D18/7; 455/566,
455/575.1, 575.3

See application file for complete search history.
